ESCALATOR HANDRAIL

Walter F. Masek and William F. Richardson, Coffeyville, Kans., assignors to Multiscope, Inc., Coffeyville, Kans., a corporation of Kansas

Application January 31, 1949, Serial No. 73,818

13 Claims. (Cl. 198—16)

1

This invention pertains to hand rails for moving stairways and the like.

In the co-pending application of Walter F. Masek, Serial Number 662,223, filed April 18, 1946, now Patent No. 2,545,741, granted March 20, 1951, it is proposed to form the moving hand rail for a moving stairway of sections of coiled spring, suitably joined end-to-end so as to form an endless loop. The external appearance of the joined sections of coiled spring is such that it appears to be a continuous spring, the respective turns of which lie contiguous one with the other in straight travel, but when turning about an internal radius, the respective turns separate slightly at their exterior. While such a hand rail is quite desirable for moving stairway installations where the exposed portions of the hand rail are rectilinear, it is obvious that if such a hand rail were exposed in that region which is turning about an inside radius, the fingers of a passenger's hand would be liable to be pinched when the hand rail passes from a curved portion of its orbit into a straight portion. Consequently, in the use of hand rails as disclosed in the aforesaid patent, it is imperative to conceal the hand rail at portions of its orbit where decreases in curvature are taking place. Moreover, the closely compacted relation of the respective turns of the coil spring, in the arrangement provided by the aforesaid patent do not admit of flexing the hand rail about a radius which is exterior to the endless loop.

An object of this invention is to provide such a hand rail which may be flexed in either direction.

Another object is to provide an improved guard for a moving hand rail which will minimize the likelihood that hands or fingers may be caught or pinched between the hand rail and a fixed co-operating part.

A further object is to provide improved guiding means, to guide the travel of the hand rail.

Another object is to provide a flexible hand rail of improved construction.

Further objects will appear from the following description, in which an illustrative embodiment of this invention will be set forth. It is understood, however, that this invention is susceptible of various embodiments, within the scope of the appended claims, without departing from the principle or spirit of the invention.

The embodiment to be described is illustrated in the accompanying drawings, in which:

Figure 1 is a side view, partly in section, of a hand rail structure embodying this invention;

Figure 2 is a section on line 2—2 of Figure 1;

Figure 3 is an enlarged detail of Figure 1;

Figure 4 is a sectional view of a modified form of hand rail section;

2

Figure 5 is a plan view of a guard element embracing the movable hand rail at the termini of exposed reaches of the latter; and

Figure 6 is a right end view of the guard shown in Figure 5.

In accordance with this invention, generally stated, a flexible hand rail is formed of a series of filamentary convolutions, in closely but substantially spaced (i. e. slightly separated) relation, and substantially parallel to each other, and maintained in this relation by flexible means to the end that the rail may flex on radii whose centres are either above or below the rail. Such a series of filamentary convolutions may be provided by a helical coil of wire, having its turns slightly spaced from one another, or it may consist of separate rings, held in their proper relation by a flexible support. The hand rail is made in sections, which are joined together to form a continuous length, having its ends joined to provide a loop. The means for joining the sections also provide attachment for supporting means, in the form of slide shoes. A supporting guide rail is provided on which said shoes may travel, and said guide rail carries a metallic strip or ribbon forming a smooth contact face for said shoes.

As in the hand rail disclosed in the aforesaid Patent No. 2,545,741, the endless loop of hand rail sections is driven about and confined to its orbit by a suitable sprocket-driven drive chain. The chain is arranged at the inner periphery of the hand rail loop, and the orbit of the hand rail is determined by entracking guide elements adjacent the chain, upon a fixed track or guide rail. With such an arrangement where the guide elements are located on the inside of the endless loop, it is evident that when the hand rail loop bends about a radius located within the loop, the respective rings of the hand rail separate at their outermost radii. Conversely, when the orbit of the hand rail bends about a radius located outside the loop, adjacent rings of the hand rail must move toward each other at their outer increments. Consequently, in order to adapt such a hand rail for bending about a radius which lies exterior to the loop, some space must be left between adjacent rings or turns. The leaving of any such space between adjacent turns may permit the entrance of dirt or other articles, or the flesh of the passengers' fingers, between the adjacent rings, and also may, in the case of a flexible hand rail, cause rattling of the sections. Accordingly, the present invention contemplates the filling of the spaces between the adjacent rings with yieldable cushion material such as rubber, which may be and preferably is in the form of an internal flexible sleeve, having ribs which extend between adjacent metallic rings to

an extent such that foreign materials cannot enter or become caught between the rings, but which will none the less yield to permit the rings to move relative to each other.

Referring now to the drawings, in the arrangement shown in Figure 1, the numeral 1 designates a helical coil of wire having its successive turns slightly spaced from one another. This provides the hand rail element which is grasped by the passengers on the escalator. As the spaces between the turns of the coil 1 may permit the entrance of dirt and other articles, or allow the turns to rattle on each other, an internal flexible sleeve 2 is provided which is shaped to conform to the interior contour of the element 1, and has portions extending into the spaces between the turns, as shown in Figure 3, to close these spaces against the entrance of foreign matter.

In the arrangement of Figure 1, the sleeve 2 is formed of rubber, or other similarly flexible material, and is provided with external grooves 3 and internal grooves 4 to render it easily flexible with the coil 1. The outer surface of the sleeve is formed with a helical depression 5, in which the turns of the coil 1 are seated. The grooves 3 form together a continuous helix following that of the depression 5. The grooves 4 are also shown as forming a helix, following that of the grooves 3, with its turns spaced between those of the outer groove. The grooves 3 and 4 may, however, be formed as parallel ring grooves, each in a single plane. This renders the sleeve 2 very flexible, as only the limited portions thereof between adjacent grooves must yield as the coil 1 bends, and there is very little stretching or compression of the material involved.

It will also be noted that by deepening the outer groove 3 to pass clear through the wall of the sleeve, the latter becomes a helical strip following the turns of the coil 1, and lodged between adjacent turns. This arrangement will also serve to close the spaces between the turns.

The several sections of coil spring 1 are mounted upon a roller chain 20, driven by a suitable sprocket, not shown, so as to move the hand rail about a defined orbit. The orbit is defined, as later described in detail, by fixed guide elements located on the inside of the loop of hand rail. Accordingly, when the orbit bends on a radius whose center lies externally to the loop of hand rail, the increments of the respective turns in coil 1 which are most remote from chain 20 must move toward each other. The degree of spacing between the respective turns of coil 1 is thus determined by the degree of bend about external centers which the hand rail will be required to travel. In no event can the spacing be less than sufficient to permit bending of the loop on the required radius, with adjacent turns of coil 1 substantially in contact at their increments remote from chain 20. It is also preferable to make the spacing as small as possible, consistent with the requirements of bending.

The end portion of the sleeve 2 is formed with a gap 6 exposing a portion of the inner contour of one or more of the turns of the coil 1, for attachment thereto of supporting means for the hand rail. Such means is provided by a coupling block 7, having its upper surface formed with grooves 8 fitting the turns of the coil 1, so that the latter may be seated therein. A screw or bolt 9 extends upward through the block 7 to the interior of coils 1, between the tips of their adjacent end turns, at the junction of successive sections of the hand rail. A coupling cap 10 is

provided with grooves 11, matching the interior contour of one or more end turns of successive coil 1. This cap has a threaded opening so as to provide a nut for the screw 9. This arrangement provides clamping means adapted to secure two successive hand rail sections together, and supporting means provided by the block 7.

The block 7 has lateral extensions which carry a pair of slide shoes 12. These shoes are preferably constructed of a good wearing material, such as laminated synthetic plastic. They are arranged for cooperation with a guide rail 13 extending along the path that the hand rail is to follow, in the usual manner. The rail 13 may be of any suitable design. In the drawings it is shown as an extruded aluminum shape. In order to provide for wear and reduce friction, the guide rail or track 13 is provided, where it is engaged by the shoes 12, with a facing in the form of a strip or ribbon 14 of spring steel or similar material. This provides a smoother surface, free from kinks or similar irregularities, which will have a long life, and which is replaceable when worn. The bearing faces of the shoes 12 may have a slight concave curvature, as shown in Figure 2, so as to bear at their ends only, whereby they may follow curves in the track without tendency to wobble.

In the arrangement of Figure 4, the sleeve 42 is of rubber, or like material, and is molded directly into the coil 1. In this case the sleeve may be made relatively thin in radial depth, and no grooving is necessary, as the slight amount of stretching and compression can be accommodated by selecting a suitable grade of material. In this case also, the coil 1, instead of being formed as a helix, may be a series of separate rings held in place by the sleeve 42. While the sleeve may be molded into the coil 1 and actually bonded to the rings, it may also be formed separately and then assembled to the coil by collapsing it preparatory to insertion.

Where the hand rail moves out of operative position at the end of a flight, a guard 15 is mounted on the guide rail 13 to force the removal of a passenger's hand from the hand rail at this point. This guard has an opening 16 into which the hand rail moves, said opening being in a front face 17 which slopes upward in the direction of travel of the hand rail. The guard 15 is made of rubber, or like material, having a coefficient of friction substantially higher than the exposed metallic surface of the hand rail 1. Thus, when the hand of a passenger, gripping the hand rail, encounters the guard 15, the hand will be forced to slide on the hand rail in preference to sliding along the guard. The coefficient of friction of the exposed surface of the guard 15, being relatively much higher than that of the exposed surface of the hand rail, thus urges the passenger to release the hand rail. Moreover, the relative coefficients of friction are such that the hand rail cannot draw the passenger's hand past or into the guard, or pinch the same thereat.

It will be seen, therefore, that this invention accomplishes its objects in providing a hand rail structure which is cheap to make, simple to erect, and durable and safe in operation. The sectional hand rail, as well as the track structure, is easily adaptable to high-rate production methods of manufacture, and the erection assembly is simple. The resulting continuous hand rail is flexible, to pass easily around turns. Its gripping surface is smooth, but the depressions between turns provide a secure grip. At the same time

the guard, through its high friction, effectively releases the hand before any danger of injury can arise.

Having thus described the invention, what is claimed and desired to be secured by Letters Patent is:

1. In an escalator hand rail structure, in combination, a flexible hand rail arranged to travel with the escalator, and a guard positioned at a locus along the orbit of said hand rail and provided with an opening into which said hand rail travels, the front face of said guard being formed to slope upward in the direction of travel so as to release the hand of a passenger from said hand rail, and said front face being of a material having a coefficient of friction substantially greater than the grip surface of said hand rail.

2. A traveling hand rail of the character described, comprising, a series of closely spaced filamentary convolutions in substantially coaxial relation, and a flexible tubular member coaxially arranged in engagement with the interior of said filamentary convolutions.

3. A traveling hand rail of the character described, comprising, a series of closely spaced filamentary convolutions in substantially coaxial relation, and a flexible tubular member coaxially arranged in engagement with the interior of said filamentary convolutions and having portions extending between said filamentary convolutions.

4. A traveling hand rail of the character described, comprising, a series of closely spaced filamentary convolutions in substantially coaxial relation, and resilient elements conforming to the interior portions of said filamentary convolutions and extending into the spaces therebetween.

5. An escalator hand rail structure, comprising a sectional hand rail element, each section including a series of rings held in closely spaced substantially coaxial relation, resilient means conforming to the interior portions of said rings and extending into the spaces therebetween, shoes movably supporting said element, clamping means on said shoes securing adjacent sections of said element together and to said shoes, a supporting guide rail along which said shoes travel, and a guard on said guide rail having an opening into which said element travels and a sloping front face having a substantially higher coefficient of friction than that of said rings adapted to remove a passenger's hand from said element as it enters said opening.

6. An escalator hand rail structure, comprising a sectional hand rail element, each section including a series of rings of uniform radius, flexible means on the interior of said rings for holding adjacent ones of said rings in closely spaced substantially coaxial relation, shoes movably supporting said element, clamping means on said

shoes having grooves in which the inner and outer contours of the end rings of adjacent sections of said element are seated, and a supporting guide rail along which said shoes travel.

7. A traveling hand rail of the character described, comprising a series of closely spaced filamentary convolutions in substantially coaxial relation forming collectively an extended cylinder, and a rubber sleeve within said cylinder and engaging the interior portions of said filamentary convolutions.

8. A traveling hand rail of the character described, comprising a helical-coil spring having a substantial part of its exterior exposed to provide a grip surface, and a flexible insert for said spring engaging the coil interiorly at said grip surface and adapted to flex therewith.

9. A traveling hand rail of the character described, comprising a helical-coil spring having a substantial part of its exterior exposed to provide a grip surface, and a flexible insert for said spring engaging the coil interiorly at said grip surface, said insert having portions extending between the turns of said spring.

10. A traveling hand rail of the character described, comprising a helical-coil spring, and a sleeve fitting the interior of the coil and peripherally grooved to render it flexible with said spring.

11. A sectional element for a hand rail of the character described, comprising a helical-coil spring, and a flexible-sleeve insert therefor constructed and arranged to close the gaps between the turns of said spring.

12. A guard for an escalator hand rail of the character described, said guard arranged to extend about the exposed surface of the handrail and having a coefficient of friction substantially greater than the exposed surface of the hand rail.

13. The combination with an escalator hand rail having an exposed surface of metal, of a guard constructed of rubber and having an upwardly sloping front face arranged to extend around the hand rail, said exposed surface of metal having a lesser coefficient of friction than said front face of said guard.
